UNITED STATES PATENT OFFICE.

LIPA FEINGOLD AND DAVID FEINGOLD, OF BROOKLYN, NEW YORK.

DESIGN FOR A RING.

Application filed March 29, 1924. Serial No. 9,110. Term of patent 14 years.

To all whom it may concern:

Be it known that we, LIPA FEINGOLD and DAVID FEINGOLD, citizens of the United States, residing at Brooklyn, in the county of Kings and State of New York, have invented a new, original, and ornamental Design for Rings, as shown in the accompanying drawing and described in the following specification.

Figure 1 is a side elevation of a ring embodying our design.

Figure 2 is an edge view of the same.

We claim:

The ornamental design for a ring as shown.

LIPA FEINGOLD.
DAVID FEINGOLD.

Witnesses:

GEORGE SCHLATT,
LILLIAN MARTIN.
